FIG. 1

FIG. 2

FIG. 3

FIG. 4

FIG. 5

FIGURE 1 is a front elevational view of a combined refrigerator and air conditioner showing my new design;

FIGURE 2 is a fragmentary top plan view thereof as shown in FIGURE 1;

FIGURE 3 is a side elevational view thereof as shown in FIGURE 1;

FIGURE 4 is a fragmentary front elevational view of a modified form of the combined refrigerator and air conditioner of FIGURE 1 wherein the difference resides in the appearance of the air deflecting vanes, and it is to be understood that the remaining portion of the housing is identical to the form shown in FIGURE 1; and

FIGURE 5 is an enlarged fragmentary top plan view of the modified form shown in FIGURE 4.

The parallel lines on the face of the door panel shown in FIGURE 1 represent conventional grooves.

The undisclosed rear is unornamented except for the longitudinal parallel alignment of conventional louvers.

We claim:

The ornamental design for a combined refrigerator and air conditioner, as shown and described.
